UNITED STATES PATENT OFFICE.

MARTIN L. MAXWELL, OF GOODWATER, MISSOURI.

DRAG-SAW.

977,028.

Specification of Letters Patent. Patented Nov. 29, 1910.

Application filed January 16, 1908. Serial No. 411,187.

To all whom it may concern:

Be it known that I, MARTIN L. MAXWELL, citizen of the United States, residing at Goodwater, in the county of Iron and State 5 of Missouri, have invented certain new and useful Improvements in Drag-Saws, of which the following is a specification.

This invention comprehends certain new and useful improvements in drag saws designed particularly for use in sawing logs, and the invention has for its object a simple, durable and efficient construction of apparatus of this character, which may be operated by steam, compressed air or any other 15 power and which will be composed of comparatively few parts that may be cheaply manufactured and readily assembled and set up in position for use.

With this and other objects in view as will 20 more fully appear as the description proceeds, the invention consists in certain constructions, arrangements and combinations of the parts that I shall hereinafter describe and claim:

25 For a full understanding of the invention, reference is to be had to the following description and accompanying drawings, in which:

Figure 1 is a side elevation of my improved sawing machine, parts being broken away; Fig. 2 is a top plan view thereof; Fig. 3 is an enlarged detail sectional view showing the gearing connection between the driving shaft and a miter gear wheel hereinafter described; Fig. 4 is a horizontal sectional view, the section being taken through the case in which parts are journaled; and, Fig. 5 is a detail perspective view of a portion of the stock of the apparatus and the 35 slide block which it supports. Fig. 6 is a fragmentary detail perspective view of one end of the rack and a portion of the saw attached thereto, showing the manner in which the saw is mounted on the rack.

40 Corresponding and like parts are referred to in the following description and indicated in all the views of the drawings by the same reference characters.

45 Referring to the drawings, the numeral 1 designates the stock of my improved sawing apparatus, said stock being provided at one end with relatively stationary clamping prongs 2 designed to penetrate the log to be sawed.

50 3 designates a slide block which is mounted to move longitudinally on the stock 1 and

which may be held at the required adjustment thereon by a set screw 4. A relatively movable clamping arm 5 is pivotally mounted on the slide block 3 and is operatively connected to a hand lever 6 by which the 55 said clamping arm 5 may be swung into operative engagement with the log, as clearly illustrated in the drawings, the extremity of said arm 5 being formed with a spur as shown. In order to adapt the clamping arms for logs of different diameters, a guide 7 is pivoted to the slide block 3, and a clamping screw 8 works through the movable clamping arm 5 and is received in the slot 70 of said guide so as to secure the clamping arm 5 at the proper adjustment.

A vertically disposed case 9 is secured to or formed on the stock 1, and the stock is provided beyond and in the rear of said case with a tubular extension 10 in which a drive shaft 11 is journaled. The rear end of the drive shaft 11 may be formed with one section 12 of a universal joint, or otherwise adapted for connection with a source 80 of power (not shown), whatever the same may be. At its opposite end, the drive shaft 11 is provided with a bevel pinion 13 meshing with the miter gear wheel 14 mounted within the case 9. The gear wheel 14 is secured on a shaft 15, and on the same shaft is a spur pinion 16 which meshes with the interior teeth of an endless rack frame 17 secured by bolts or rivets to the rear end of the saw blade 18.

90 In order to properly guide the rack frame 17 on the spur pinion 16, an arm is secured to the shaft 15 outside of the pinion 16, and projects upwardly from the pinion and carries at its upper end a roller 19 designed to bear against the outer side of the frame 17. Another arm projects forwardly from and is pivoted to the shaft of the roller 19, said last named arm carrying at its forward end a roller 20 which also bears against the outer side of the frame. A contractile spring 21 is connected to a pin projecting outwardly from the forward end of said last named arm and also to the bearing for the outer end of the shaft 15, the roller 20 being yieldingly mounted thereby so as to pass the end of the rack frame in the gyratory movement that is imparted to the saw.

105 In order to maintain the saw blade 18 in proper contact with the log as the incision deepens, I provide a presser arm 22 which is pivoted at its rear end to the case 9 and

which is provided at its forward or free end with a grooved roller 23 bearing on the upper edge of the saw blade. The tension spring 24 is secured to the stock or case at 5 one end, and to the arm 22 at its other end so as to pull down on the arm and exert the proper tension on the blade.

A collar 25 is secured on the rear end of the tubular extension 10 of the stock, and 10 said collar is provided with a vertically disposed sleeve 26, which accommodates the upright or standard 24^a, a set screw working in the sleeve and impinging against the standard so as to hold the parts in proper 15 vertically adjustable positions. The standard 24^a is pivotally connected at its lower end to a quadrant 25^a and legs 26^a are pivotally connected to said quadrant and are designed to be embedded in the ground or 20 other support and provided with means for holding the shaft 11 at the proper elevation, with the standard and quadrant at the necessary inclination with respect to the quadrant and legs as may be necessary to the 25 inclination of the ground where the device is installed.

In the practical operation of my improved sawing apparatus, it will be understood that power applied to the shaft 11 will rotate the 30 same through the instrumentality of the bevel pinion 13 and miter gear wheel 4 and will drive the shaft 15 so as to rotate the spur pinion 16 and effect a reciprocating and vibratory movement of the saw blade to saw 35 the log. As the blade cuts into the log, it will press downwardly to maintain a proper cutting action by means of the presser arm 22. Manifestly the apparatus is susceptible 40 to use on logs of different sizes, by the adjustment rendered possible by the slide block 13 and the pivoted clamping arm 5.

Having thus described the invention, what is claimed as new is:

1. A sawing apparatus of the character 45 described, comprising a stock adapted to be secured at one end to a log, a slide block mounted on said stock, means for holding said block at different adjustments on the stock, a movable clamping arm pivotally

mounted on the slide block, a hand lever for 50 manipulating said clamping arm, means for securing said arm to the slide block at different adjustments, and a saw and actuating means therefor supported by said stock.

2. A sawing apparatus of the character 55 described, comprising a stock, means for supporting said stock in operative relation to a log, a case secured to said stock, the stock being provided beyond the case with a tubular extension, a shaft journaled in said extension, a bevel pinion secured to one end of said shaft, another shaft journaled in the case, a miter wheel mounted on said last named shaft and meshing with the pinion, a spur pinion secured to said last named shaft, 60 a blade, an endless rack frame secured to the rear end of the saw blade, and two rollers adapted to travel on the outside of the saw frame, one of said rollers having a connection with the last named shaft, and the other 65 roller being yieldingly mounted, as and for the purpose set forth.

3. A sawing apparatus of the character 70 described, comprising a stock, means for supporting said stock in operative relation 75 to a log, a case secured to said stock, a shaft journaled in said case, means for turning said shaft, a spur pinion secured to said shaft, a blade, an endless rack frame with 80 interior teeth, said frame being secured to the rear end of the blade, the pinion meshing with said rack, a roller carried by said arm and bearing upon the outer surface of the rack, a forwardly projecting arm pivoted to the first named arm, a roller carried 85 by the forwardly projecting arm and also bearing against the outer side of the rack, and a contractile spring secured to said last named arm and arranged to hold the last named roller under tension against the outer 90 surface of the rack.

In testimony whereof I affix my signature in presence of two witnesses.

MARTIN L. MAXWELL. [L.S.]
